UNITED STATES PATENT OFFICE.

FRANK E. WALL, OF DETROIT, MICHIGAN, ASSIGNOR TO GABRIEL STEEL COMPANY, OF DETROIT, MICHIGAN, A CORPORATION OF MICHIGAN.

SCAFFOLD BRACKET.

Application filed November 26, 1923. Serial No. 677,149.

This invention relates to supports and refers more particularly to scaffold brackets.

An object of the invention is to provide a strong and durable bracket that may be easily and quickly attached to a wall or other suitable structure for supporting scaffold boards or planks upon which the workmen are adapted to stand.

Another object is to provide a simple form 10 of bracket which may be compactly folded when not in use and which will be automatically locked in closed position when folded so that it will not accidentally open up while being transported from one point to another.

15 With the above and other objects in view the invention consists in certain novel features of construction, combinations and arrangements of parts as will be more fully described and particularly pointed out in the 20 appended claims.

In the accompanying drawing:

Figure 1 is a perspective view of a scaffold bracket embodying my invention applied to a wall;

25 Figure 2 is a top plan view of the bracket when in open position;

Figure 3 is a side elevation thereof when folded;

30 Figure 4 is an enlarged detail view of the upper ends of the connection between the braces and the supporting bar.

Referring now to the drawing in which like characters of reference designate corresponding parts throughout the several views, 35 the numeral 1 designates a scaffold bracket embodying my invention attached to a wall 2 of a building.

The bracket preferably comprises a bar 3 for supporting the scaffold boards 4, a hook 5 for connecting the bar to the usual studding or uprights 6 to which the boards 7 of the wall are secured; a pair of braces 7' having depending feet 8 for engagement with the boards 7, and links 9 and 10 respectively connecting the braces 7' to the bar 3.

40 The hook 5 is preferably provided with a relatively long shank 11 that extends longitudinally of the bar 3 and that is rigidly secured thereto at spaced points by suitable rivets 12. Projecting laterally from the upper edge of the bar 3 is a longitudinally extending reinforcing flange 13 that is preferably provided at spaced points with openings 14 for receiving suitable securing ele-

ments for the scaffold boards 4 and that preferably terminates at the outer end of the bar in an upstanding lug 15 for preventing the boards 4 from accidentally slipping off from the bar 3 when no securing elements 40 are used.

The braces 7' are preferably pivotally connected by a pivot 16 to opposite sides of the bar 3 adjacent to the lug 15 and are also preferably provided with laterally projecting reinforcing flanges 17 that extend longitudinally thereof and that are bent downwardly at the lower free ends of the braces to form the feet 8 for abutting the boards 7 of the wall. The lower free ends of the 50 braces 7' are cut away at an angle to provide bearing edges for the feet while the flanges 17 are preferably bent over at their upper ends against the braces 7' as shown at 17' to reinforce the pivotal connection 55 with the bar 3. The braces preferably diverge from the pivot 16 and are rigidly connected adjacent to the feet 8 by a cross-bar 18 that reinforces the braces and that retains the feet in proper spaced relation. 60

In order that the bracket may be readily folded when not in use, the parallel links 9 are pivoted at one end upon the outermost rivet 12 and are also preferably connected by a pin 19 to the links 10 which diverge 65 from the pin 19 and are pivotally connected by suitable rivets 20 to the braces 7' adjacent to the crossbar 18.

When it is desired to fold the bracket, the pivot 19 is moved toward the pivot 16 so that the bar 3 and braces 7' will be drawn together. In order that the bracket will be held in folded position, the pivot 19 is preferably moved by the bar 3 beyond the plane 70 of the pivots 16 and 20 until the bar 3 engages a bowed cross-bar 21 that is rigidly secured to the braces 7'. A spacer 22 surrounds the pivot 19 between the links 9 and is adapted to be engaged by the bar 3 when the same is used to move the pivot 19 to 75 off center position. The links 10 are constructed of spring metal so that when the pivot 19 is moved beyond the plane of the pivots 16 and 20 the links 9 will pull the pivot 19 slightly toward the pivots 20 and 80 will cause the links 10 to bow and yieldably hold the pivot 19 in off-center position.

85 While it is believed that from the foregoing description, the nature and advantages of the invention will be readily apparent, 90

ent, I desire to have it understood that I do not limit myself to what is herein shown and described and that such changes may be resorted to when desired as fall within the 5 scope of what is claimed.

What I claim as my invention is:

1. A scaffold bracket comprising a scaffold supporting member, braces pivotally connected to said supporting member, pivotally connected links extending between said braces and supporting member, the pivot for said links being adapted to be moved between said braces, and a bar extending between said braces and adapted to 10 be engaged by said supporting member for limiting the movement of said pivot, one of said links being yieldable for holding said supporting member against said bar.
2. A scaffold bracket comprising a scaffold supporting member, braces pivotally connected to said member, a bar rigidly connecting said braces, links pivotally connected to said supporting member, yieldable links pivotally connected to said braces, a pivot 15 member connecting said yieldable links to the links aforesaid, said pivot member being adapted to be moved between said braces, and means for limiting the movement of said pivot member.
3. In a scaffold bracket, the combination with a scaffold supporting member and a brace pivoted thereto, of a link pivoted to the brace, a link pivoted to the supporting member, and a pivot element connecting said 20 links, said pivot element being adapted to be moved beyond the plane of the pivots for the brace and first-mentioned link to off-center position whereby the last-mentioned link will cause the first-mentioned link to bow and yieldably hold the said pivot element in 40 off-center position.
4. A bracket comprising a supporting member, braces pivotally connected thereto, a bar extending transversely of said braces, and foldable means pivotally connected to 45 said member and braces adapted to be folded between said braces, said means including an element for yieldably holding the member against said bar.
5. A bracket comprising a supporting bar, 50 braces pivotally connected thereto, a pair of spaced yieldable links pivotally connected to said braces, spaced links pivotally connected to said bar, and a pivot member connecting said yieldable links to the last mentioned 55 links, said pivot being movable to off-centre position with respect to the pivots for the braces and first mentioned links for holding the braces and bar in closed position.
6. A bracket comprising a supporting bar, 60 a brace pivotally connected thereto, a link pivotally connected to said brace, a link pivotally connected to said bar, and a connection between said links adapted to be moved to off-centre position, one of said links being 65 yieldable to hold said connection in off-centre position, whereby said bar and brace will be held in closed position.

In testimony whereof I affix my signature.

FRANK E. WALL.
